CONTAINER FOR DEODORANT DISPENSING
BOTTLES

Urban J. Jacquet, Oakland, Calif.

Application May 23, 1949, Serial No. 2,832

Term of patent 14 years

(Cl. D16—2)

To all whom it may concern:

Be it known that I, Urban J. Jacquet, a citizen of the United States, residing at Oakland, in the county of Alameda and State of California, have invented a new, original, and ornamental Design for a Container for Deodorant Dispensing Bottles, of which the following is a specification, reference being had to the accompanying drawing, forming part thereof.

Figures 1, 2, 3, and 4 are, respectively, front, side, back, and top plan views of a container for deodorant dispenser bottles, showing my new design.

I claim:

The ornamental design for a container for deodorant dispensing bottles, as shown.

URBAN J. JACQUET.
